(57) **CLAIM**

The ornamental design for an energy storage battery, as shown and described.

DESCRIPTION

FIG. 1 is a perspective view of an energy storage battery taken from an upper right side, showing my new design; FIG. 2 is another perspective view thereof, taken from a lower left side;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a partially enlarged view of the part encircled FIG. 9 in FIG. 1; and,

FIG. 10 is a partially enlarged view of the part encircled FIG. 10 in FIG. 2.

The dashed broken lines illustrate portions of the energy storage battery which form no part of the claimed design. The dot-dash broken lines are intended to show the boundaries of enlarged views and form no part of the claimed design.
